Primary Examiner — Catherine Ho(74) *Attorney, Agent, or Firm* — Tucker Ellis LLP(57) **CLAIM**

The ornamental design for a self-service terminal, as shown and described.

DESCRIPTION

FIG. 1 is a perspective view of a self-service terminal, showing my new design;

FIG. 2 is an enlarged bottom view of the self-service terminal;

FIG. 3 is an enlarged top view of the self-service terminal;

FIG. 4 is a rear view of the self-service terminal;

FIG. 5 is a right side view of the self-service terminal;

FIG. 6 is a front view of the self-service terminal; and,

FIG. 7 is a left side view of the self-service terminal.

The broken line portion in the drawings is included to show portions of the self-service terminal that form no part of the claimed design.

1 Claim, 7 Drawing Sheets(56)
